UNITED STATES PATENT OFFICE

2,529,018

DOWEL MAKING MACHINE

William P. Hancharik, Upper Black Eddy, Pa.

Application September 8, 1945, Serial No. 615,188

2 Claims. (Cl. 142—54)

1

The present invention relates to new and useful improvements in machines for making dowels, forming tenons on stock and for performing similar mill work, and the invention has for its primary object to provide a machine of this character of relatively small and compact form adapted for mounting on a work bench and capable of easily and quickly performing its function.

An important object of the present invention is to provide means for interchangeably mounting a tool bit holder and a facing cutter in the machine to adapt the machine for either cutting dowels of a predetermined diameter or for cutting tenons or rounding either one or both ends of stock of either round or square shape.

A further object of this invention is to provide a novel construction for mounting guides of various diameters in the machine for the dowels while the same are being cut.

An additional object is to provide an adjustable front guide for the stock and adapted to accommodate stock of various sizes.

A still further object is to provide a device of this character of simple and practical construction, which is efficient and reliable in operation, relatively inexpensive to manufacture and install in operative position on a work bench and which otherwise is well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a longitudinal sectional view showing the tool bit mounting in position for cutting dowels,

Figure 2 is a fragmentary longitudinal sectional view showing a facing cutter mounted in position in the machine,

Figure 3 is a top plan view,

Figure 4 is a transverse sectional view taken substantially on a line 4—4 of Figure 1,

Figure 5 is a fragmentary front elevational view of the front guide for square-shaped stock,

Figure 6 is a transverse sectional view taken substantially on a line 6—6 of Figure 2,

Figure 7 is a fragmentary front elevational view of the front guide provided for round stock, and

Figure 8 is a side elevational view of the diameter gauge for setting the tool bit.

2

Referring now to the drawings in detail, wherein, for the purpose of illustration, I have disclosed a preferred embodiment of the invention, the numeral 5 designates a base plate 5 adapted for attaching in a desired position on a work bench by means of the bolt openings 6.

Rising from the rear end of the base 5 is a bearing body 7 having a bore 8 therein and in which is mounted a bushing 9 for rotatably receiving the tubular shank 10 having an enlarged tool-supporting head 11 at its front end. The head 11 is provided with a plurality of radially extending openings 12 in which tool bits 13 are adjustably mounted and secured in radially adjusted position by means of set screws 14.

The tool head 11 is formed with a socket 15 defined by a shoulder 16 at its inner end and flared, as at 17, at the outer or front end of the tool head. The bore of the shank 10, at its junction with the socket 15, is also flared, as indicated at 18.

A tubular adapter 19 is positioned in the bore of the shank 10 and has its front end flared, as indicated at 20, corresponding to the flared portion 18 of the tool head 11. The rear end of the adapter 19 is formed with a flange 21 which abuts the rear end of the shank 10.

A pulley 22 is positioned on the rear end of the shank 10 behind the bearing body 7, the pulley being formed with a flange 23 by means of which the pulley is secured to the shank 10 as well as to the adapter 19 by means of a set-screw 24.

The adapter 19 forms a rear guide for the dowel 25 cut by the tool bits 13, said guide having an internal diameter corresponding to the diameter of the dowels.

Extending transversely at the front of the base plate 5 are a pair of spaced, parallel guide rails 26 between which is slidably positioned a rib 27 formed on the bottom of a front guide designated generally at 28. The guide 28 is preferably constructed of a metal angle iron member 29 forming the bottom and rear of the guide and in the angle of which is secured a wooden block 30.

The block 30, as well as the rear wall of the angle iron member 29, is formed with aligned openings 31 which may be of square shape as shown in Figure 5 in the drawings to conformably receive square-shaped stock 32, or the openings 31 may be round, as indicated at 33 in Figure 7 of the drawings, for receiving round stock as indicated at 34 in Figure 2.

The openings 31 and 33 are of graduated size for accommodating stock of various sizes and the several openings of the front guide 28 are secured

in aligned positions with the tool head 11 by slidably adjusting the guide on the track 26 and securing the guide in adjusted position by means of a set-screw 35.

The bearing body 7 is formed with an annular oil chamber 36 which surrounds the bushing 9 and is supplied by means of an oil cup 37.

A guard 38 is mounted for sliding movement on the bearing body 7 to cover both the cutting head 11 and the pulley 22, suitable openings (not shown) being formed in the guard to accommodate a drive belt for the pulley and the oil cup 37.

In the operation of the device, a diameter gauge 38' is provided which is inserted in the rear end of the shank 10 to position one of the stepped portions 38'' of the gauge at the inner ends of the bits 13, and the bits adjusted in accordance with the diameter of the dowel to be cut. The gauge 38' is then removed and the adapter 19 of an internal diameter corresponding to the diameter of the dowel to be cut is then inserted in the shank 10 and secured in position by the set-screw 24.

The front guide 28 is then adjusted on the rails 26 to bring one of the openings 31 into alignment with the tool head 11 according to the size of the stock being used and the end of the stock slidably moved through the guide 28 into cutting engagement with the tool bits 13, whereupon the dowel 25 will be cut at the end of the stock.

When it is desired to cut a tenon 39 with a facing cutter on round stock 34, for instance, the front gauge 40 having the round opening 33 is then placed in position on the rails 26, and the tool bits 13 removed from the cutter head 11 and a facing cutter 41 placed in position in the socket 15 and secured therein by set-screws 42. Round stock may be held by hand against turning in the front gauge 40.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claims.

What I claim is:

1. A wood-working device comprising a base having a journal member, a tool support including a tubular shank journaled in said member, means for securing a cutter in one end of the tool support, a drive member attached to the other end of the tool support, and a tubular guide secured in the shank and adapted for holding one end of the work, transverse guide rails on the base and a second guide having aligned gauge openings therein of different sizes for receiving the other end of work of different sizes, said second guide being slidably adjustable on said rails transversely of the axis of said tubular guide to position work of different sizes in axial alignment with said tubular guide.
2. A woodworking tool for turning down work of rectangular and round shape in cross section, respectively, comprising a base having a journal member thereon, a tool support including a tubular shank journaled in said member, means for securing a cutter on one end of the tool support, a tubular guide secured in said shank for slidably holding one end of the work for feeding to said cutter, a second guide having an opening therein for holding the other end of the work as it is fed to the cutter, said second guide comprising an apertured angle member and a similarly apertured block secured to said angle member with the aperture in the block aligned with the aperture in said angle member.

WILLIAM P. HANCHARIK.
